UNITED STATES PATENT OFFICE.

JOHN RICHARD HOSKINS, OF BARTLESVILLE, OKLAHOMA.

DUMP BAILER.

Application filed May 26, 1924. Serial No. 716,056.

To all whom it may concern:

Be it known that I, JOHN RICHARD HOSKINS, a citizen of the United States of America, residing at Bartlesville, in the county of Washington and State of Oklahoma, have invented certain new and useful Improvements in Dump Bailers, of which the following is a specification.

This invention relates to an improvement in dump bailers, of that type designed to deliver desired material to the bottom of an oil or gas well for plugging the same.

The main feature of the present invention is the provision of means whereby the material being carried to the bottom of the well is protected against the oil or water in the well during transit, and is automatically delivered when the bailer has reached the bottom of the well.

The invention further comprehends a particular means whereby the bottom of the bailer proper is held in closed position during transit and released through a trip mechanism, in turn operated by contact with the bottom of the well, the trip mechanism being adjustable in its control of the bailer bottom to cause the force of the latter necessary to release the bailer bottom to be variable at will.

The invention is illustrated in the accompanying drawings, in which:

Fig. 1 is a view in elevation of the improved dump bailer.

Fig. 2 is a vertical central section of the same.

Figs. 3, 4, 5, and 6, are respectively enlarged transverse sections on the lines 3—3, 4—4, 5—5, and 6—6 of Fig. 1.

The improved dump bailer comprises a bailer section proper as 1, which, for the purposes of the present invention, may be an ordinary pipe section interiorly threaded at the upper end as at 2, whereby to permit the connection of additional sections for increasing the capacity of the bailer proper and for lowering the latter into position.

The bailer section proper, which is cylindrical in form, is extended as a half cylindrical portion 3, the latter being fully open on one side and at the bottom to permit the contents of the bailer proper to reach the bottom of the well through gravitational delivery. Secured within the cylindrical portion 1 of the bailer proper is an annular lining 4 formed at the lower edge with a hinged support 5, on which is hinged a

bottom or closure 6. The lining member 4 is removably secured within the bailer section 1 and the closure 6 forms a bottom to thereby provide a closed receptacle into which the material to be delivered to the bottom of the well is initially placed.

The closure 6 is supported through the medium of bars 7 arranged in spaced relation and connected by cross bars 8 to provide a unitary bar structure. The bars 7 at their upper ends are connected by a pin 9 which extends loosely through a loop 10 formed in a strap 11 secured to the underside of the closure 6, whereby the bars, when the closure is in operative position, may be supported near the free end of the closure, as clearly shown in Fig. 2. The bars 7 near their lower ends are provided with a transverse connecting pin 12, which beyond the bars is mounted in the free ends of links 13, which at their opposite ends are pivotally supported on studs 14 secured in the extension 3 of the bailer proper. Beyond the connecting pin 12, the bars 7 are extended in angularly related bar sections 15, which latter are of short length and connected by a transverse locking pin 16.

Through the medium of the connection described, it is apparent that the supporting bars 7 and links 13 form a toggle lever connection, and that so long as the connecting point of the respective portions of the toggle connection, that is, the connecting pin 12, is inwardly of a line between the pin 9 and the pivot studs 14, the closure will remain in closed position.

A trip bar 17 is slidably mounted in the extension 3, being held between abutments 18, on which are secured bridge bars 20, thus providing a channel in which the trip bar is slidably held. This trip bar is formed at its lower end with a lateral or enlarged terminal 21, and at a point immediately adjacent the locking pin 16 with a latch in the form of an angle plate 22 secured to the trip bar and having an outstanding and depending terminal 23 adapted when the parts are in set position to engage the locking pin 16 and prevent relative outward movement of the connecting pin 12. The locking pin 16 may, if desired, be squared or formed with an angular surface to permit accurate holding cooperation of the latch therewith. Immediately below the latch, the trip bar is formed with an outwardly and downwardly curved portion 24, and

immediately beneath said portion with an inwardly curved portion 25. The outwardly curved portion serves as an operating face, which, in the upward movement 5 of the trip bar, serves to laterally displace the connecting pin 12 by engaging the locking pin 16, the movement continuing until the connecting pin 12 is carried beyond the center when the parts pivot about the studs 10 14, the closure opens, and the connecting pin 12 finally seats itself in the reduced portion 25.

The device is shown in operative or set position in Fig. 2, from which it will be 15 noted that the latch 22 is in cooperation with the locking pin 16 and hence the release of the closure cannot be effected. In this position, the enlarged end 21 of the trip bar 17 extends below the extension 3, so 20 that as the bailer is lowered into the well, the projecting end of the trip will be engaged by the bottom of the well and the trip bar moved upwardly, with the effect to release the closure in the manner described and permit the gravitational discharge 25 of its contents.

If for any reason the material at the bottom of the well should be of such soft consistency as to permit the projecting end of the trip to pass thereinto without operating the trip, the invention contemplates the use of a plate 26, which is adapted for pivotal connection at 27 with the trip bar so as to be turned up at right angles thereto, and when in such position to engage with the trip bar to prevent further upward movement. A broad surface is thus presented which on contacting with even soft material will compel movement of the trip bar. 30 The wall of the extension 3 is provided at diametrically opposite points with studs 28, adapted to engage the trip plate 26 when the latter has been moved a sufficient distance to cause the trip bar to effect the release of the parts, the trip plate being thus 35 swung down into inoperative position to permit a free flow of the material to the bottom of the well.

It is of course apparent that the more 40 nearly the connecting pin 12 is arranged in line with the pins 9 and 14, the easier the release may be effected, and to control the degree of force required to effect the release, adjusting pins 29 are mounted in 45 threaded openings 30 in the wall of the extension 3, these adjusting pins 30 underlying the ends of the links 13 which engage the connecting pin 12. Through obvious adjustment of these pins 29, the connecting pin 12 may be spaced the desired distance 50 from the wall of the extension 3, thereby permitting a greater or less movement of the connecting pin to break the joint. Thus the trip bar may be made more or less sensitive in its action in breaking the joint 55

and in actual delivery of the material controlled in accordance with the bottom conditions in the well.

As will be plain from Figs. 3, 4, and 5, the extension 3 is substantially semi-cylindrical and the operating parts are housed within such section, thereby providing an opening the full length of the section through which the material delivered on the trip of the closure will find its way to 75 the bottom of the well. It is further apparent that as the closure is tripped, the locking parts described move first outwardly and then downwardly and inwardly, and that during this movement the closure proper is deflecting the material away from such operating parts. Thus the material may be delivered intact to the bottom of the well without interference from the operating parts. 85

What I claim is:

1. A dump bailer having a pivotal closure, a toggle lever support for said closure, and a trip bar wholly free of connection with said support and slidably movable for 90 operating said support to break the joint.

2. A dump bailer having a pivotal closure, a toggle lever support for said closure, a trip bar for operating said support to break the joint, and a latch carried by said trip bar to prevent breaking of the joint 95 when the trip bar is in inoperative position.

3. A dump bailer having a pivotal closure, a toggle lever support for said closure, 100 a trip bar wholly free of connection with said support and slidably movable for operating said support to break the joint, and means for adjusting the angular relation of the toggle members to control the extent of 105 movement in the breaking action.

4. A dump bailer having a pivotal closure, a toggle lever support for said closure, a trip bar for operating said support to break the joint, and a trip plate movably 110 connected to the trip bar and adapted to be arranged at right angles thereto to be engaged by the material at the bottom of the well for operating the trip bar.

5. A dump bailer having a movable bottom, supporting bars connected therewith, a connecting pin uniting said bars near their lower ends, links pivotally connected to the bailer and to said connecting pin, said bars having angular extensions beyond the connecting pin, a locking pin connecting said angular extensions, a trip bar slidably in the bailer under contact with the well bottom, said trip bar being formed in part to engage the locking pin and deflect the 120 connecting pin to break the joint. 125

6. A dump bailer having a movable bottom, supporting bars connected therewith, a connecting pin uniting said bars near their lower ends, links pivotally connected 130

to the bailer and to said connecting pin, said bars having angular extensions beyond the connecting pin, a locking pin connecting said angular extensions, a trip bar slideable in the bailer under contact with the well bottom, said trip bar being formed in part to engage the locking pin and deflect the connecting pin to break the joint, and a latch carried by the trip bar to engage the locking pin when the trip bar is in inoperative position to prevent breaking of the joint.

7. A dump bailer having a movable bottom, supporting bars connected therewith, a connecting pin uniting said bars near their lower ends, links pivotally connected to the bailer and to said connecting pin, said bars having angular extensions beyond the connecting pin, a locking pin connecting said angular extensions, a trip bar slideable in the bailer under contact with the well bottom, said trip bar being formed in part to engage the locking pin and deflect the connecting pin to break the joint, and adjusting screws threaded in the bailer and adapted to engage the connecting pin to adjust same laterally with respect to the bailer.

8. A dump bailer having a movable bottom, supporting bars connected therewith, a connecting pin uniting said bars near their lower ends, links pivotally connected to the bailer and to said connecting pin, said bars having angular extensions beyond

the connecting pin, a locking pin connecting said angular extensions, a trip bar slideable in the bailer under contact with the well bottom, said trip bar being formed in part to engage the locking pin and deflect the connecting pin to break the joint, and a latch carried by the trip bar to engage the locking pin when the trip bar is in inoperative position to prevent breaking of the joint, a plate pivotally connected to the trip bar and adapted to be held at right angles thereto against upward pressure.

9. A dump bailer having a movable bottom, supporting bars connected therewith, a connecting pin uniting said bars near their lower ends, links pivotally connected to the bailer and to said connecting pin, said bars having angular extensions beyond the connecting pin, a locking pin connecting said angular extensions, a trip bar slideable in the bailer under contact with the well bottom, said trip bar being formed in part to engage the locking pin and deflect the connecting pin to break the joint, a latch carried by the trip bar to engage the locking pin when the trip bar is in inoperative position to prevent breaking of the joint, a plate pivotally connected to the trip bar and adapted to be held at right angles thereto against upward pressure, and means on the bailer to engage and deflect said plate following operation of the trip bar.

In testimony whereof I affix my signature.
JOHN RICHARD HOSKINS.
